UNITED STATES PATENT OFFICE

IRENE F. BRISACHE, OF NEW YORK, N. Y.

CATAMENIAL SACK

Application filed March 31, 1930. Serial No. 440,408.

This invention relates to improvements in catamenial sacks, and more particularly to an improved device made from thin rubber having means for receiving a deodorizing powder and for positively clamping an absorbent pad therein, said sack being so constructed and made of soft pliable material that it may be instantly cleaned in cold water, dried and used immediately thereafter.

10 An object of the invention is to provide an improved catamenial sack or sanitary pad support which will be molded from thin rubber, and which will be provided with molded deodorant receiving pockets in the inner or

15 upper surface of the sack.

Another object of the invention is to provide an improved catamenial sack or sanitary pad support which will be molded from thin rubber and will be formed with a slight bead 20 on its edges to reinforce the same, said sack being formed of rubber prevents the pad when moist from having any change in temperature.

25 A further object of the invention is to provide an improved catamenial sack which will be made from thin rubber by molding, and which will be so formed that when the same is enclosing a sanitary pad, the pressure necessary to hold the sack in operative position, 30 will be sufficient to positively and resiliently clamp the opposite ends of the pad to hold the same in the sack.

35 A still further object of the invention is to provide an improved form of catamenial sack which will positively clamp a sanitary pad within the same, and will be provided with reinforced openings at the opposite ends of the sack, through which the attaching ends of the pad may be inserted whereby the sack 40 and pad may be positioned when desired.

Other objects will appear as the description proceeds.

In the accompanying drawings which form a part of my application,

45 Figure 1 is a plan view of the molded blank

from which my improved catamenial sack is formed;

Figure 2 is a plan view of my improved catamenial sack with a sanitary pad positioned therein;

Figure 3 is a sectional view taken on the line 3—3 of Figure 2, and

Figure 4 is a sectional view taken on the line 4—4 of Figure 2.

Like characters of reference are used throughout the following specification and the accompanying drawings to designate corresponding parts.

In carrying out my invention, I provide a catamenial sack having a body portion 1 formed with oppositely disposed laterally extending pad clamping strips 2 at the opposite ends of said body portion, and having a slight bead 3 formed along all of the edges of the body portion and pad clamping strips.

A mold is utilized to mold my improved catamenial sack which is formed of thin rubber, and during the molding operation the bead 3 is formed about the edges of the sack, as well as the depressed pockets 4 for holding powdered deodorizing material. The pockets 4 are disposed only in the upper surface of the body portion 1 and in the central portion thereof.

After the rubber blank is molded, the oppositely disposed laterally extending pad clamping strips 2 are folded inwardly across the ends of the body portion 1 until they overlap, thereby forming the openings 5 at the opposite ends of the sack through which the attaching ends 6 of the sanitary pad 7 are extended. The overlapping pad clamping strips 2 are then vulcanized together, thereby forming a complete pocket or sack for the reception of a sanitary pad 7. The four corners of the sack are formed on a bias, as clearly illustrated in the drawings, and are secured to the overlying portions of the clamping strip 2.

From the foregoing description, it will be

apparent that when the catamenial sack is to be used, a powdered deodorant will be sprinkled in the pockets 4 in the upper surface of the body portion 1, and a sanitary pad 7 will be inserted within the sack with its oppositely extending attaching ends 6 extended through the openings 5 in the sack, and the said ends drawn taut. Due to the overlapping pad clamping strips, and to the fact 10 that the ends of the pad 7 are securely wedged into the opposite ends of the sack, it will be readily seen that upon pulling out on the ends 6, the said pad clamping strips will securely clamp down on the opposite ends of 15 the pad to securely hold the same in position within the sack. The usual stress or pressure on the ends of the pad when adjusting the same for wearing, will be sufficient to cause the sack to efficiently and properly retain the pad within the same. The beaded edges of the sack will have a natural tendency to assist in supporting the pad in its proper position within the sack at all times.

It will be understood that many minor 25 changes in detail of construction may be resorted to without departure from the spirit of the invention.

Having thus described my invention what I claim as new and desire to secure by Letters 30 Patent of the United States is:

1. A rubber catamenial sack comprising a flat body portion having substantially parallel side edges and end edges, the said body portion having its corners angularly cut at 35 points between its adjacent sides and ends, and pad clamping means overlying said body portion parallel to the plane thereof consisting of transversely disposed strips attached to the end portions of the parallel side edges 40 and to the edges of the cut corners and unattached at the ends of the body portion, forming openings at the ends of the sack, the inner unattached edges of the strips being arranged on a bias above the body portion 45 thereby forming V-shaped clamping strips, whereby a pad may be positioned flat upon the body portion with its ends positively clamped between the clamping strips and the body portion, and the gauze attaching strips 50 of the pad extended through the openings in the opposite ends of the sack.

2. A rubber catamenial sack comprising a flat body portion having substantially parallel side edges and end edges, the said body 55 portion having its corners angularly cut at points between its adjacent sides and ends, depressed deodorant receiving pockets formed in the upper surface of said body portion, and pad clamping means overlying said body 60 portion parallel to the plane thereof consisting of transversely disposed strips attached to the end portions of the parallel side edges and to the edges of the cut corners and unattached at the ends of the body portion forming 65 openings at the ends of the sack, where-

by a pad may be positioned flat upon the body portion with its ends positively clamped between the clamping strips and the body portion with the gauze attaching strips of the pad extended through the openings in the 70 opposite ends of the sack.

3. The combination as set forth in claim 2, and the inner unattached edges of the strips being arranged on a bias above the body portion thereby forming V-shaped clamping 75 strips.

In testimony whereof I affix my signature.
IRENE F. BRISACHE.
